UNITED STATES PATENT OFFICE.

DAVID W. KENDALL, OF GRAND RAPIDS, MICHIGAN, ASSIGNOR TO THE
PHOENIX FURNITURE COMPANY, OF SAME PLACE.

DESIGN FOR A CHAIR.

SPECIFICATION forming part of Design No. 27,596, dated August 31, 1897.

Application filed July 24, 1897. Serial No. 645,869. Term of patent 3½ years.

To all whom it may concern:

Be it known that I, DAVID W. KENDALL, a citizen of the United States, residing at Grand Rapids, in the county of Kent and State of Michigan, have invented and produced a new and original Design for Chairs, of which the following is a specification, reference being had to the accompanying drawing, showing a part thereof.

10 The figure is a perspective of my chair, which I deem sufficient to fully illustrate my design.

The leading features of my design consist of arms A, broad and approximately square at the outer end and scrolled at the back end to approach the back C as a narrow curved arm, as illustrated. These arms are supported at the front end upon legs B, which are approximately a diamond shape as applied to the body of the chair and are curved to produce a graceful appearance, substan-

tially as shown. The arms are further supported by being attached at the small end to the back of the chair and by a series of ornamental spindles D, set upon an incline to support the outer edge of the arms. 25

The back legs B' may be ordinary turned legs and the frame of the chair may be strengthened by the ordinary turned spindles F G. Under the front of the seat E, I place 30 a rail I of substantially the form shown in the drawing.

The back of the chair C is made of substantially the form shown in the drawing and is ornamented with an appropriate scroll, as C'. 35

What I claim as new is—

The design for a chair substantially as shown and described.

DAVID W. KENDALL.

In presence of—
ANDREW ALLGIER,
I. J. CILLEY.
